UNITED STATES PATENT OFFICE.

MILTON B. CROWELL, OF NEWPORT NEWS, ASSIGNOR OF ONE-HALF TO
CAROLINE M. BICKFORD, OF HAMPTON, VIRGINIA.

PEDAL ATTACHMENT FOR ORGANS.

SPECIFICATION forming part of Letters Patent No. 447,560, dated March 3, 1891.

Application filed October 9, 1890. Serial No. 367,519. (No model.)

To all whom it may concern:

Be it known that I, MILTON B. CROWELL, a citizen of the United States, and a resident of Newport News, Warwick county, Virginia, 5 have invented certain Improvements in Pedal Attachments for Organs, of which the following is a specification.

My invention consists of certain improvements in that class of pedal attachments which 10 are carried by the player's stool and can be folded up under the stool when not in use, the objects of my invention being to construct such a pedal attachment for application to an organ, to provide for the operation of the bellows of the main organ by means of a hand-lever carried by the stool, to insure the firm anchoring of the stool and its pedal attachment to the main organ, and to provide for the disposal of all of the parts within the limits 15 of the stool when the attachment is not in use. These objects I attain in the manner herein-after set forth, reference being had to the accompanying drawings, in which—

Figure 1 is a transverse section of an organ-stool with pedal attachment in accordance 25 with my invention, the pedal attachment being shown as adjusted in position for use. Fig. 2 is a similar section showing the attachment folded as when not in use. Fig. 3 is a rear view of the stool. Fig. 4 is a plan view 30 of the stool and its attachment, the latter being in the position shown in Fig. 1; and Fig. 5 is a sectional view illustrating a modification of the invention.

35 A represents the top, and A' the opposite end supports, of an ordinary player's stool for use with an organ. Extending from one of the supports A' of the stool to the other near the front of the stool and adjacent to 40 the floor is a rod a, to which is hung a frame B, this frame being rectangular in the present instance and being secured to the rod a by one or more turn-buckles b, so that it can be readily removed when such removal is desired, or can be swung on the rod either to a 45 horizontal position, so as to rest on the floor and project in front of the stool, as shown in Fig. 1, or to a vertical position, so as to be turned up within the limits of the stool, as 50 shown in Fig. 2. This frame carries a series of pedals D, each of which is adapted to actu-

ate a valve in a reed-box F, also carried by the frame, said reed-box receiving its air-supply from the wind-chest of the main organ X through the medium of a flexible pipe or tube x, as shown by dotted lines in Fig. 1.

To bearings on the front of the frame B are adapted rock-shafts d, each of which has two arms f and g, the arms f bearing upon the foot-boards y of the bellows-actuating mechanism of the main organ. To the arm g of each rock-shaft is connected a cord or wire h, which passes round guide-pulleys i on the frame B and on the cross-bar G of the stool, one of these cords or wires h being connected 65 to one arm and the other to the opposite arm of a lever J, which is hung to an arm m, pivoted to the cross-bar H of the stool, the upper end of this arm m swinging into a socket n on said cross-bar H, and being retained in position 70 therein by a pin p, Fig. 3.

The lever J projects beyond the end support A' of the stool, and has a suitable handle by which it may be manipulated, said lever thus serving as a means for operating the bellows 75 of the main organ, and thus providing a supply of air for the latter and also for the reed-box of the pedal attachment.

In order that the stool and its attachment may be rigidly anchored in their proper position in front of the organ when the attachment is in use, the frame B has at each end 80 projecting tongues or fingers s, which are inserted beneath the frame of the organ, and thus serve to retain the frame B and the parts 85 carried thereby close to the floor and prevent any displacement, either of the frame or stool, such as might otherwise be caused by the movement of the player.

When it is not desired to use the pedal attachment, the stool is withdrawn until the tongues s are pulled from beneath the frame of the organ, whereupon on detaching the tube x the pedal attachment is free to be turned up under the stool, as shown in Fig. 2. 95 Upon withdrawing the pin p from the socket-plate n the arm m and the pumping-lever J, carried thereby, can be thrown down to the position shown by dotted lines in Fig. 3, so that said lever will not project beyond the 100 end frame or support of the stool.

Although I prefer to use in carrying out

my invention the rock-shafts *d*, having arms *f* and *g*, simple bell-crank levers may be substituted therefor, if desired, the cords *h* in this case running backward at an angle, so as to give the desired spread when the cords are carried up to the lever *J*, and a single rock-shaft or bell-crank lever might in some cases be used instead of the duplex arrangement shown, although the latter is preferred, as most organs have a duplex foot-board for operating the bellows mechanism.

Although in carrying out my invention the reed-box is preferably located beneath the pedals, so as to render the attachment as compact as possible, this construction need not necessarily be adhered to in all cases. For instance, in Fig. 5 I have shown a reed-box *F'* located in the rear of the frame *B'*, the pedals *D'* in this case being in the form of bell-crank levers, so that they may properly act upon the valve-stems projecting from said reed-box.

Having thus described my invention, I claim and desire to secure by Letters Patent—

1. The combination, in a pedal attachment for organs, of the stool, a pedal attachment carried by said stool and projecting in front of the same, a pumping-lever hung to the stool, and means whereby the movement of said lever can be transmitted to the bellows mechanism of the main organ, substantially as specified.

2. The combination, in a pedal attachment for organs, of the stool, a pedal attachment carried by said stool and projecting in front of the same, a pumping-lever hung to the stool, means whereby the movement of said lever is transmitted to the bellows mechanism of the main organ, and a pipe or conduit affording a communication between the wind-chest of the main organ and the reed-box of the pedal attachment, substantially as specified.

3. The combination of the stool, the pedal attachment having a frame connected to the stool, lever mechanism carried by said frame for acting on the foot-boards of the main organ, a pumping-lever hung to the stool, and cords or like connections between said pumping-lever and said foot-board levers, substantially as specified.

4. The combination of the stool with a frame connected thereto and projecting beyond the same, pedals mounted in said frame, and a reed-box located beneath said pedals, substantially as specified.

5. The combination of the stool, a frame pivoted thereto and carrying a reed-box and pedals, a pumping-lever hung to the stool, and means for transmitting the movement of said pumping-lever to the foot-boards of the main organ, substantially as specified.

6. The combination of the stool, the pedal attachment carried by said stool and projecting in front of the same, and tongues or fingers projecting from said pedal attachment, so as to be inserted beneath the frame of the main organ, and thus serve as anchors for said pedal attachment, substantially as specified.

7. The combination of the stool, the pedal attachment carried thereby, the pumping-lever carried by an arm hung to the stool, and a detachable retaining device for said arm, whereby the arm and its lever may be moved inward, so that said lever will not project beyond the end frame of the stool, substantially as specified.

In testimony whereof I have signed my name to this specification in the presence of two subscribing witnesses.

MILTON B. CROWELL.
